W. McKNIGHT.
ADJUSTER FOR VENETIAN BLINDS.
APPLICATION FILED FEB. 29, 1908.

909,927.

Patented Jan. 19, 1909.

UNITED STATES PATENT OFFICE.

WALTER MCKNIGHT, OF DAYTON, OHIO.

ADJUSTER FOR VENETIAN BLINDS.

No. 909,927.

Specification of Letters Patent.

Patented Jan. 19, 1909.

Application filed February 29, 1908. Serial No. 418,524.

To all whom it may concern:

Be it known that I, WALTER MCKNIGHT, a citizen of the United States, residing at Dayton, in the county of Montgomery and 5 State of Ohio, have invented certain new and useful Improvements in Adjusters for Venetian Blinds, of which the following is a specification.

My invention relates to Venetian blinds, 10 and particularly to an adjusting device therefor, adapted to hold the slats of the blind at any degree of inclination.

The object of the invention is to greatly simplify the structure as well as the means 15 and mode of operation of such devices, whereby they will not only be cheapened in construction, but will be rendered more efficient and positive in operation, easily operated and unlikely to get out of repair.

20 It is customary to provide a friction or brake device on the rock bar of such blinds, to hold the blind in adjusted condition, and while such devices usually work well when new, the life of the brake device is very brief, and after a little use it fails to retain 25 the slats in adjusted position but permits the slats to gradually return to open position.

One of the primary objects of this invention is to provide a lock device adapted to 30 positively hold the slats in adjusted position, at any degree of inclination, and inclined in either direction.

A further object is to provide such a device which will be automatic in operation, 35 permitting the blind to be closed in the usual manner, but which will automatically lock the blind in an extreme position to which it has been adjusted, and to provide means for 40 readily releasing the slats that they may return to normal.

With the above primary and other incidental objects in view, as will appear from the specification, the invention consists of 45 the means, mechanism, construction, and mode of operation, or their equivalents, as hereinafter described and set forth in the claims.

Figure 1 is a perspective view of the device forming the subject matter of this application, removed from the blind. Fig. 2 is a transverse sectional view showing the parts 50 in normal or open positions. Fig. 3 is a simi-

lar view of the parts in their operated positions. Fig. 4 is a side elevation of the rock 55 bar and lock mechanism in operated position.

Like parts are indicated by similar characters of reference throughout the several views.

Referring to the drawings, 1 is the frame 60 or support bar adapted to be secured to the top of the window frame, and on which all parts of the blind are supported. Adjacent to each end of the support bar 1 is a pendent bracket 2, in which is journaled a rock bar 3, 65 from opposite edges of which are dependent tapes 4 supporting a series of slats 5. By rocking the bar 3 on its trunnions, the slats 5 are inclined and caused to over-lap each other to close the blind. By varying the degree of inclination of the slats, more or less light may be admitted through the blind, and intermediate the slats 5. This is the usual construction of Venetian blinds, and forms 70 no part of the invention, except in combination with the hereinafter described lock mechanism as pointed out in the claims. 75

Secured to the upper side of the rock bar is a notched segment 6 having teeth in the form of ratchet teeth. The teeth of the segment 6 are arranged preferably in two series extending in opposite directions from the center of the segment as shown in Figs. 2 and 3. Attached to the under side of the support bar 1 is a bracket 7 to which is pivoted a 80 pawl lever 8 engaging the teeth of the notched segment 6. A spring 9 tends to press the pawl lever 8 into engagement with the segment. The spring 9 is preferably arranged as in Fig. 1 with one end engaging the bracket and the opposite end engaging the pawl lever, the portion intermediate the ends being coiled about the pivotal connection 10 of the pawl lever. However, instead 85 of the spring 9 a coil spring as indicated at 95 11 in Fig. 4 might be employed. The pawl lever is extended past the pivotal connection in the form of an arm 12 to which is attached a cord 13 by means of which the pawl lever may be lifted from engagement with the notched segment 6. The teeth of the segment 6 are in the form of ratchet teeth and are turned in opposite directions from the center. The pawl lever 8 normally engages the V shaped notch intermediate the 100 two series of ratchet teeth, in the center of

105

the segment. When in this position the slats 5 are in their wide open position. The slats may be closed or inclined in either direction in the usual manner by pulling 5 either of the tapes 4 or a tilting cord not shown to oscillate the rock bar 3.

When the bar 3 is oscillated the pawl lever 8 will ride freely over the teeth of the segment 6, while the bar is being oscillated to 10 close the blind, but the pawl lever will engage the teeth to prevent the return movement of the bar 3 to normal. By the teeth of the segment being arranged in oppositely disposed series, the pawl 8 will ride over the 15 teeth freely in either direction from the center, and will hold the bar in any degree of inclination. Whatever the degree of adjustment, the slats may be freely moved toward closed position, and will be positively retained in the extreme position to which they have been adjusted. When it is desired to 20 return the blind to normal, the cord 13 is pulled to lift the pawl lever from the segment 6, when the blind may be returned to 25 normal in the usual manner.

One of the features of the device is that it may be applied to existing blinds, without in any way changing or modifying the structure of the blind. The device is of 30 small proportion and its location is such that it will be scarcely observed by a person on the floor of the room, thereby being entirely unobjectionable, on account of appearance, which is important in devices of this character.

From the above description it will be apparent that there is thus produced a device of the character described, possessing the particular features of advantage before 40 enumerated as desirable, but which obviously is susceptible of modification in its form, proportion, detail construction, and arrangement of parts, without departing from the principle involved or sacrificing 45 any of its advantages.

Having thus described my invention, I claim:

1. In a device for maintaining the slats of Venetian blinds in angular adjustment, the 50 combination with a blind of a notched segment the teeth of which are arranged in two reverse series adapted to oscillate therewith, a pawl lever having a fixed support engaging said segment to hold the blind in the 55 angular position to which it has been adjusted, and means for disengaging said parts, substantially as specified.

2. In a device for maintaining the slats of Venetian blinds in angular adjustment, the 60 combination with a blind including an oscillating member, of a notched segment on said member, a pawl lever, a stationary support for said lever, said pawl lever being adapted to ride freely over said notched segment

when the blind is operated from open to 65 closed condition but adapted to engage said segment and prevent the reverse movement of the blind to open position until disengaged from said segment, substantially as specified.

70

3. In a device for maintaining the slats of Venetian blinds in angular adjustment, the combination with a blind including an oscillatory member, of a part having series of ratchet teeth and carried on said member, a 75 pawl engaging said ratchet teeth and serving to hold the blind in its operated or closed position, a means for disengaging said pawl at any point of adjustment whereby said blind will be permitted to return to 80 normal or open position, substantially as specified.

4. In a device for maintaining the slats of Venetian blinds in angular adjustment, the combination with a blind of a movable 85 ratchet segment and a pawl engaging same, the ratchet teeth in said segment being arranged in two series, the teeth of the respective series being turned in opposite directions from a common point, substantially 90 as and for the purpose specified.

5. In a device of the character described, the combination with a blind of a movable ratchet segment and a pawl engaging same, the ratchet teeth in said segment being arranged in two series, the teeth of the respective series being turned in opposite directions from the center, said pawl normally resting intermediate said series, and adapted to ride over the teeth in either direction 100 from the center, and to engage the teeth to retain the parts in adjusted position, and means for releasing said pawl, substantially as specified.

6. In a device for maintaining the slats of 105 Venetian blinds in angular position, the combination with a blind of a movable ratchet segment and a pawl lever engaging same, said lever extending beyond the pivotal point thereof, a spring holding said pawl lever in engagement with the ratchet segment, an operating cord attached to the pawl lever beyond the pivotal point and serving to disengage the pawl from said ratchet segment, substantially as specified.

110

7. In a device of the character described, a blind including an oscillatory member, means for positively retaining said blind in different degrees of adjustment including a pawl and a ratchet member, the teeth of which 120 are arranged in two reverse series and means for positively lifting said pawl from engagement with said ratchet, substantially as specified.

8. In a device of the character described, a 125 blind including an oscillatory member, means for positively retaining said blind in different degrees of adjustment including a pawl

and a ratchet member, the teeth of said ratchet member being turned in opposite directions from the center, whereby said pawl and ratchet may be relatively moved in either direction and means to release the pawl whereby the parts may be returned to normal position, substantially as specified.

In testimony whereof, I have hereunto set my hand this 15th day of February A. D. 1908.

WALTER McKNIGHT.
